UNITED STATES PATENT OFFICE.

CHARLES FRANK BORSCHNECK, OF KNOXVILLE, PENNSYLVANIA.

ELECTRIC DISPLAY SYSTEM.

1,110,872.

Specification of Letters Patent. Patented Sept. 15, 1914.

Application filed January 11, 1913. Serial No. 741,368.

To all whom it may concern:

Be it known that I, CHARLES FRANK BORSCHNECK, a citizen of the United States, and residing in the borough of Knoxville, 5 in the county of Allegheny and State of Pennsylvania, have invented or discovered new and useful Improvements in Electric Display Systems, of which the following is a specification.

10 My invention relates to apparatus whereby letters or other characters or representations are caused to traverse an electric sign or display board.

Generally speaking, it comprises switching 15 mechanism whereby the electric circuits controlling the lights on the display board are operated to produce the traveling effects. Means, connected with the display board, are provided, by which a terminal or group 20 of terminals, representing one or more letters or other characters, is selected and caused to travel over a field of contacts whereby the corresponding letter or character is caused to travel over the display board.

25 The selective operation may be accomplished by hand, as by means of any convenient type of key-board; where, as in reporting current news, the wording or characters are not constant. But for use where the character of the matter displayed is constant, as 30 in advertising, an automatic control or selective mechanism is desirable. For the latter purpose I show two forms of devices, one of which consists of a bank or line of 35 brushes adapted to contact with a contact block or other means for establishing a corresponding number of circuits which, when closed, operate the switching apparatus of one or more display boards. The contacts 40 are made and broken by means of a traveling strip or ribbon of insulating material provided with slots or perforations, properly placed, through which said brushes intermittently make contact, thus setting 45 groups of terminals of the switching apparatus which produce the desired letters or characters on the display board. The other form 50 consists of a group of pneumatic relays adapted to make and break the terminal setting circuits and controlled by a perforated strip or ribbon traveling over the former.

The switching apparatus, of which I show two forms comprises a pair of adjacent sup-

ports, one of which moves. One of said supports is provided with stationary contacts which are severally in circuit with the individual lights on the display board. The other support is provided with terminals capable of extension to contact with said fixed contacts, and means, controlled by the selective mechanism above referred to, are provided for extending or retracting the movable terminals whereby the various lamp circuits are completed as may be required. 65 Novel means for mounting and controlling the movable terminals are provided, and novel features of construction and arrangement of elements and parts will appear from the following description.

70 In the accompanying drawings, Figure 1 is a perspective of one form of the switching apparatus, the display board and its connections with the switching apparatus being shown diagrammatically; Fig. 2 is a 75 broken section of the switching apparatus along the line II—II in Fig. 4, showing the setting apparatus in position to set one of the movable terminals; Fig. 3 is an enlarged detail of the same showing the setting apparatus in its inoperative position; Fig. 4 is a vertical section of the switching apparatus along the line IV—IV in Fig. 1, and a diagrammatic view of the automatic electric selective mechanism connected therewith; 80 Fig. 5 is a detail of Fig. 3 showing one of the movable terminals in inoperative position; Fig. 6 is a similar view showing the same in operative position; Fig. 7 is a section along the line VII—VII in Fig. 6; Fig. 90 8 is a bottom plan view looking in the direction of the arrow in Fig. 5; Fig. 9 is a view partially in section along the line IX—IX in Fig. 10 and partially diagrammatic showing a modified form of switching apparatus 95 and an electro-pneumatic selective apparatus; Fig. 10 is an end elevation of the switching apparatus partially in section along line X—X in Fig. 9, one of the disks being partially broken away, and Fig. 11 is 100 a longitudinal section of one of the members of the electro-pneumatic selective device.

The following is a detailed description of the drawings, reference being first had to Figs. 1-8 inclusive. I will first describe the switching apparatus shown in said figures, which consists of two concentric rings or supports A and B, one of which, such as the

outer ring A, is fixed while the other ring, such as B, rotates. As a convenient method of mounting said rings I may provide the web 1 of the ring A with a central aperture 5 or journal box 2, provided with an insulating bushing in which is journaled a shaft 3 concentrically secured to the web 4 of the ring B. The shaft 3 is geared to a dynamo C.

10 The fixed ring A is provided with a plurality of groups or lines of fixed contact members 5 set transversely of the ring and extending through to the inner perimeter of the same and insulated therefrom. Each 15 line or group of contacts 5 corresponds in number to the lights or lamps 6 in each row on the display board D transverse to the direction of travel. Thus if the travel of the display on board D is in the direction 20 of the arrow, then the number of contacts 5 in each group in ring A would be equal to the number of lamps 6 in the corresponding vertical row on board D, and the number of groups of contacts, which are spaced 25 apart about the ring A, would correspond to the number of vertical rows of lamps on board D. Each contact 5 is connected by a wire 7 to one of the lamps 6 which it controls. In the drawings, for the sake of 30 clearness, I have shown but one group of contacts connected up respectively to their individual lamps, but it will be understood that in practice each contact is wired to its corresponding lamp.

35 The lamps 6 of the display board D are connected by a common return wire 8 with a source of electric current, such as generator E, whose other pole is connected by wire 9 and brush 10 with the ring B.

40 The rotating ring B is provided with a plurality of groups of terminals 11, each group containing the same number of individuals as the groups of contacts 5 and being similarly placed transversely of the 45 ring. There are, however, preferably a greater number of groups of terminals 11 than of contacts 5. Said terminals 11 are slidably seated in radial slots 12 in the ring B and are themselves slotted longitudinally to seat the coiled springs 13. The upper ends of said springs contact with shoulders 14 in slots 12 whereby said springs 13 tend to throw said terminals 11 outwardly to drag over and contact with the 55 inner ends of contacts 5. The inner ends of terminals 11 are provided with spring triggers 15 which are adapted to snap over the inner ends of slots 12 and hold said terminals 11 retracted.

60 The apparatus for setting the movable terminals 11 is as follows. 16 is an angular bracket mounted on ring A and supporting a group of electro-magnets 17 within the ring B and transversely thereto, as clearly 65 shown in Fig. 4. The number of magnets

in the group corresponds to the number of movable terminals 11 in each transverse line or group. Each magnet 17 is provided with a centrally pivoted armature 18 whose outer end is provided with a tripper 19 which, 70 when the magnet 17 is energized is thrust down into the path of the triggers 15, tripping the same and allowing their terminals 11 to be thrown outwardly to contact with the contacts 5 in circumferential alinement 75 therewith. A coiled spring 20 normally holds the tripper 19 in its raised or inoperative position. It is thus evident that by energizing the proper magnets, the circuit of any desired lights may be completed, and 80 by selecting the proper magnets the desired combination of terminals may be set which by the rotation of the ring B will cause any desired letter or character, or series of letters or characters, to traverse the display 85 board D.

The terminals 11 once set will remain set in their operative or contacting position during the rotation of the ring B until they strike against the inward transverse projection 21 on the ring A which will automatically throw inwardly or retract out of their operative position all of the terminals 11 which have been set by the magnets, causing the triggers 15 to snap over the inner 95 ends of slots 12 locking said terminals 11 in their inoperative position. It is thus evident that at the completion of the travel of the letter or character over the display board, the corresponding movable terminals 100 are returned to their inoperative position and the proper ones reset as they pass the magnets 17.

The automatic selective apparatus, shown in Figs. 1-8 inclusive, consists of a group 105 or line of trailing brushes 22, one for each magnet 17 and connected with their respective magnets by wires 23. A common return wire 24 runs from the magnets 17 to a source of electric energy, such as a 110 battery F. 25 is a contact block or other contact member, connected by wire 26 with the battery F. The brushes 22 contact with block 25 and complete the electric circuits through the magnets 17 thus setting the 115 movable terminals 11 controlled by the individual magnets as they pass under their magnets.

27 is a strip or ribbon of paper or other insulating material which is interposed and caused to travel between the brushes 22 and block 25 to break the contact, said strip 27 being provided with perforations or slots 28 to permit intermittent contact between individual brushes 22 and the block 25. It 125 is evident that by providing the proper perforations 28 any letter, character or representation may be made to travel over the display board D.

As a convenient method of mounting and 130

operating the ribbon 27, which, for the sake of illustration, is shown as an endless belt for the continued reproduction of the same groups of letters or characters upon the display board D, I have shown an idle roll 29 and a power driven roll 30 over which the ribbon 27 is run, a tension roll 31 being provided to enable the roll 30 to operate the ribbon. The roll 30 may be driven from the 10 motor C or an independent motor synchronized therewith.

Referring now to Figs. 9, 10 and 11, I will proceed to describe the modified form of switching device illustrated in said figures. 15 I have therein substituted for the concentric rings A and B a pair of adjacent and parallel disks A' and B'. The disk A' is preferably stationary and may be provided with a base flange 32 by means of which it is secured to a bed plate G. A bolt 33 may pass through a slot in said flange 32 and engage a threaded hole in said bed plate. H is a bracket extending vertically from said bed plate. 34 is a shaft journaled in said 20 bracket H and in the center of disk A' and insulated from both. The disk B' is rigidly mounted on said shaft which in turn is rotated by means of gears 35 and 36 connecting said shaft with a dynamo C'. The disk 25 A' is provided with contact members 5^a, similar to contact members 5 of the preceding figures, said members 5^a being set in radially disposed groups transversely of the disk A', as shown, and being connected respectively to the lamps 6 of the display board D by means of wire 7^a. The contacts 5^a are insulated from the disk A' in any convenient manner. The shaft 34 is in 30 electrical circuit with all the lamps 6 of the display board D by common wire 9^a and brush 10^a. 11^a are movable contact members arranged in radially disposed groups in transverse seats 12^a in the disk B'. The 35 structure and seating of the members 11^a is similar to that already described in connection with the member 11. The setting magnets 17^a are arranged in a group as shown and mounted in the bracket H. Each magnet is provided with a pivoted armature 18^a 40 and tripper 19^a which is extended, when said magnet is energized, to trip the triggers 15^a of the terminals 11^a in a manner similar to that described in connection with the preceding figures. The position of the disk A' 45 is adjustable in relation to the disk B' by means of the slot in flange 32, thus enabling the taking up of wear and insuring a good contact between the contact members 5^a and the movable members 11^a when the latter are set. 21^a is a radial projection on the disk A' which throws the terminals 11^a into their inoperative position as they pass the same in a manner similar to that described in connection with projection 21 of the ring A. 50 The setting magnets may be controlled 55

and actuated by the selective device shown in the preceding figures, but I have shown in connection with Figs. 9, 10 and 11 an electro-pneumatic selective device which I will now describe.

37 is a block or table over which is caused to travel a ribbon or strip 27^a, shown in dotted lines, provided with properly placed perforations 28^a. The block 37 is provided with a row of orifices 38 which correspond in number to the magnets 17^a, and each communicating with a tube 39 of one of the pneumatic relays I which are also equal in number to said magnets. The structure of a relay I is as follows. The tube 39 connects 70 with a chamber 40 which in turn connects with a second chamber 41 by means of a small port 42. 43 is a diaphragm interposed between said two chambers 40 and 41 upon which rests the butt of a valve 44 which when raised closes a port 45 leading from atmosphere to said chamber 41. 46 is a tube connecting the chamber 41 to an exhaust pump or other vacuum device, not shown. The chamber 41 also communicates with the 75 interior of a bellows 47 which carries a contact plate 48 adapted, when said bellows is contracted, to make contact with the fixed contact plate 49 which is connected by the wire 23^a to the proper magnet 17^a. A common wire 24^a connects all of the relays I to all of the magnets 17^a.

It is evident that when an unperforated portion of the ribbon 27^a is passing over the orifice 38, no air enters the tube 39, the diaphragm 43 drops, the port 45 is open and the pump sucks air through port 45 and the bellows 47 is at its normal expansion. When, however, a perforation 28^a registers 80 with the orifice 38, air is sucked in through the tube 39, raising the diaphragm 43 and closing the port 45. As insufficient air is admitted through the small port 42, the air is drawn from the bellows 47, raising the plate 48 into contact with the plate 49 and completing the circuit of the magnet 17^a, and setting the terminals 11^a controlled by said magnets. As soon as the perforation 28^a passes beyond the orifice 38, the mechanism 85 assumes the position shown in Fig. 11, breaking the circuit and deenergizing the magnet 17^a. The ribbon 27^a is synchronized in its movements with the movement of the switching device.

Where a number of display boards are 90 used for the display of the same matter, I may connect the switching apparatus of each to a common selective apparatus placed in a convenient location, as in an office where 95 easily accessible, or the various switching apparatus may be controlled by a common hand-operated selective apparatus if desired. By this means I do away with the major portion of the expensive wiring now 100 used in connection with traveling display 105 110 115 120 125 130

boards and am enabled to reduce the number of selective contact brushes or pneumatic relays; otherwise it would be necessary to provide a selective brush or pneumatic relay for each lamp on the display board.

Although, for the sake of clearness, I have minutely described the embodiment of my invention illustrated in the drawings, I do not wish to limit myself thereby, but claim broadly:—

1. In combination with a plurality of electric lamps, contact members in circuit with the corresponding one of said lamps, said members being mounted in annular series, a second series of contact members adjacent to said first series adapted to be extended to contact with said first members to complete said circuits, means for extending and retracting said second members, and means for moving one of said series in relation to the other series, for the purpose described.
2. In combination with a plurality of electric lamps, contact members in circuit with the corresponding one of said lamps, said members being arranged in groups and said groups being arranged in annular series, a second series of contact members also arranged in like groups in annular series adjacent to said first series and adapted to be extended to complete said circuits, means for extending and retracting said second members, and means for moving one of said series in relation to the other series, for the purpose described.
3. In combination with a plurality of electric lamps, contact members arranged in annular series in circuit with the corresponding one of said lamps, a second contact member adapted to be extended to contact with individuals of said series, means for extending and retracting said second member, and means for establishing a rotary relationship between said series and said second member for the purpose described.
4. In combination with a plurality of electric lamps, switching apparatus comprising contact members arranged in a plurality of annular series in circuit with the corresponding one of said lamps, a contact connected to all of said lamps and adapted to be extended to contact with the members of said series of contacts, an electric magnet adapted to control the extension of said second contact, and means for establishing a rotary relationship between said series of contacts and said second contact, for the purpose described.

5. In an electric traveling display device, the combination of a plurality of lamps; a switching device comprising contact members arranged in a plurality of annular series in circuit with the corresponding one of said lamps, other annular series of contacts adjacent to said first named series and extensible into contact therewith, means for

rotating one of said sets of annular series of contacts, an electro-magnet for each of said last named series of contacts and controlling the extension of the same; and an energizing electric circuit for each of said magnets.

6. In combination with a plurality of electric lamps, contact members arranged in annular series in circuit with the corresponding one of said lamps, a second contact member adapted to be extended to contact with individuals of said series and connected to all of said lamps, means for extending said second member, means for retracting said second member after the desired contacts have been made, and means for establishing a rotary relation between said series and said second member, for the purpose described.

7. In an electric traveling display device, the combination with a plurality of lamps of a switching device comprising contact members arranged in a plurality of annular series in circuit with the corresponding one of said lamps, a second annular series of contacts extensible into contact with the members of said first series, and connected to all of said lamps, means for extending members of said second series into contact with members of said first series, and means for rotating one of said series in relation to the other series, for the purpose described.

8. In an electric traveling display device, the combination with a plurality of lamps of a switching device comprising an annular series of groups of contact members in circuit with the corresponding one of said lamps, a second annular series of groups of contacts connected to all of said lamps and individually extensible into contact with members of said first series, means for extending individuals of said second series, means for retracting the same when the desired contact has been accomplished, and means for rotating one of said series in relation to the other series, for the purpose described.

9. In combination with a plurality of electric lamps, contact members in circuit with the corresponding one of said lamps, said members being mounted in annular series, a second series of contact members adjacent to said first series adapted to complete said circuits, means for extending members of said second series into contact with said first series, and means for rotating one of said series in relation to the other series, for the purpose described.

10. In combination with a plurality of electric lamps, contact members in circuit with the corresponding one of said lamps, said members being arranged in groups and said groups being arranged in annular series, a second series of contact members also arranged in groups and said groups being arranged in annular series adjacent to said

first named annular series, means for extending individuals of said second series into contact with members of said first series, means for retracting said individuals into their inoperative position, a common connection between said second series and all of said lamps, and means for rotating one of said series in relation to the other series, for the purpose described.

Signed at Pittsburgh, Penna., this 10th 10
day of January, 1918.
